COLLOIDAL MILL

Frank G. Crane, Montague, Mich., assignor to
Frank G. Crane, Jr., Montague, Mich.

Application July 24, 1935, Serial No. 32,893

19 Claims. (Cl. 83—13)

My invention relates to colloidal mills, and more particularly to devices for homogenizing and/or viscolizing various materials.

In making color and size for coating paper it is necessary to homogenize or viscolize the material by passing the same through a valve having a restricted passage which breaks down the material in a well known manner. A pump is used to force the material through the valve, these outfits being relatively expensive. However costly, they are damaged by material containing grit or abrasives, as will be readily understood.

The main objects of my invention are:

First, to provide a viscolizer which will handle material containing grit or abrasives without injury.

Second, to provide a homogenizer which is simple in construction and efficient in operation.

Third, to provide a colloidal mill which is economical to operate, and which is capable of improving the properties of colors and the like to a remarkable degree.

I attain these objects by mechanism illustrated in the accompanying drawing in which—

25 The single figure is a view mainly in side elevation of my machine, parts being shown in section.

Referring to the drawing, 1 is a supporting frame on which are mounted a drum 2 and a motor 3 at opposite ends thereof. The motor shaft 4 and a shaft 5 are connected by a flexible coupling 6, the shaft 5 extending through packing glands 7 and 8 in the end closure plates 9 and 10 of the drum.

35 The drum has an upper inlet 11 near one end thereof and a lower outlet 12 near the other end thereof, the latter being provided with a hand valve 13 for controlling the action of the device, as will be described below. The inlet is connected to the outlet 14 of a funnel 15 by a rubber hose 40 coupling 16, leaving the funnel free to be vibrated. The funnel is provided with a straining screen (not shown) of the desired mesh.

45 The funnel is vibrated in response to the rotation of the shaft 5 by a crank 17 pivoted at 18 to the arm 19, and having its lower end provided with a follower 20 coating with a cam 21 on the shaft 5, the upper end 22 of the crank being fixed to the funnel.

50 The cam is removably mounted on the shaft for adjustment and for change as desired. Since the shaft 5 rotates at about 1750 R. P. M., the funnel is vibrated quite effectively.

55 Arranged on the shaft 5 within the drum, are a plurality of spaced parallel inclined disks 23 having milled or toothed edges in bearing coac-

tion with the inner cylindrical surface 24 of the drum. The disks are held in place by spacers 25 and end nuts 26 and 27. Thus, the disks rotate with the shaft 5 relative to the drum, the latter constituting the stator and the former the rotor of the device.

The disks are preferably inclined about 60 degrees relative to the axis of the shaft, and the teeth at the periphery of the disks are parallel to said axis. With this inclination of the disks, 10 the latter are spaced about one inch apart, the internal diameter of the bore of the stator being about four inches. The drum is slightly over one foot long in the present embodiment. The drum and disks, as well as the other parts of the device 15 subject to contact with the material, are preferably made of acid resisting metal, such as a bronze alloy.

The teeth of the disks are in sliding or bearing contact with the inner surface of the drum, 20 and are rotated at about 1750 R. P. M. relative to the latter. This machine will handle 120 gallons of color per hour, the action of the novel valves reducing the viscosity about 25%, and making the color more bright and free flowing. 25 This remarkable result is attained even with the color containing abrasive material, without injury to my machine; a decided improvement over the old type of valve which must be renewed at great expense and inconvenience even when the color contains a very slight amount of grit.

The mill by its action also reduces the particle size of the color, and thoroughly mixes it, resulting in a smooth and even coating on the paper, 35 and one that is contiguous. This is especially good in coating for insulation purposes. My invention, however, is not limited to the treatment of color, but has a wide field of application, including the viscolizing, homogenizing, emulsifying, mixing or like treatment of any material. 40

In operation, the passage of the material through the device is controlled by adjusting the hand valve 13. Thus, the flow may be changed between maximum and minimum amounts, as desired, depending upon the nature of the material and the treatment desired. There is a natural tendency for the material to flow by gravity through the machine and this tendency is augmented by the action of the disks in creating a vacuum by virtue of their peculiar position and movement in the drum.

The results attained are most remarkable, to such an extent in fact, that I am unable at the present time to explain the principal of operation of the device producing such results. The device 55

is not injuriously affected by materials containing abrasives, even when the viscosity of the material is being reduced to a considerable extent by the action of the device; a thing heretofore unknown to those skilled in the art. The advantages flowing from this feature are self evident, the greatest being the viscolizing of materials containing abrasives, without injury to the valves, each disk coating with the drum to provide a

10 valve.

I claim—

1. In a machine of the class described, the combination with a supporting frame, of a drum mounted on said frame near one end thereof, a 15 motor mounted on said frame near the other end thereof, the drum having end closures and an upper inlet near one end and a lower outlet near the other end, a shaft journalled to said end closures and coupled to the shaft of said motor, a 20 plurality of inclined disks arranged in spaced parallel relation on said shaft within the drum and having peripheral teeth slidably coacting with the inner surface of the drum, and a hand valve associated with said drum outlet.

25 2. In a machine of the class described, the combination with a supporting frame, of a drum mounted on said frame, a motor mounted on said frame, the drum having end closures and an upper inlet near one end and a lower outlet near 30 the other end, a shaft journalled to said end closures and coupled to said motor, a plurality of inclined disks arranged in spaced parallel relation on said shaft within the drum and having peripheral teeth slidably coacting with the inner 35 surface of the drum, and a hand valve associated with said drum outlet.

3. In a machine of the class described, the combination with a supporting frame, of a drum mounted on said frame near one end thereof, a 40 motor mounted on said frame near the other end thereof, the drum having end closures and an upper inlet near one end and a lower outlet near the other end, a shaft journalled to said end closures and connected to the said motor, a plurality of inclined disks arranged in spaced parallel 45 relation on said shaft within the drum and having peripheral teeth slidably coacting with the inner surface of the drum, and a valve controlling said drum outlet.

50 4. In a machine of the class described, the combination with a supporting frame, of a drum mounted on said frame, a motor mounted on said frame, the drum having end closures and an upper inlet near one end and a lower outlet near 55 the other end, a shaft journalled to said end closures connected to the said motor, a plurality of inclined disks arranged in spaced parallel relation on said shaft within the drum and having peripheral teeth slidably coacting with the inner 60 surface of the drum, and a valve controlling said drum outlet.

5. In a machine of the class described, the combination with a horizontal drum having end closures and an upper inlet near one end and a 65 lower outlet near the other end, of a motor driven shaft journalled to said end closures, a plurality of inclined disks arranged in spaced parallel relation on said shaft within the drum and having peripheral teeth slidably coacting with the inner 70 surface of the drum, and a valve controlling said drum outlet.

6. In a machine of the class described, the combination with a horizontal drum having end closures and an upper inlet near one end and a 75 lower outlet near the other end, of a motor driven

shaft journalled to said end closures, a plurality of inclined disks arranged in spaced parallel relation on said shaft within the drum and having peripheral teeth slidably coacting with the inner surface of the drum, and a hand valve controlling said drum outlet.

5

7. In a machine of the character set forth, the combination with a horizontally disposed cylindrical drum having an upper inlet at one end and a lower outlet at the other end, of end closure plates associated with the opposite ends of said drum, a shaft journalled to said end closure plates and extending through said drum, spaced disks arranged on said shaft for rotation therewith within the drum, the disks being inclined relative to said shaft and having peripheral teeth slidably coacting with the inner surface of the drum, and means acting to rotate said shaft and disks.

10

8. In a machine of the character set forth, the combination with a horizontally disposed cylindrical drum having an inlet at one end and an outlet at the other end, of a shaft extending through said drum, spaced disks arranged on said shaft for rotation therewith within the drum, the disks being inclined relative to said shaft and having peripheral teeth slidably coacting with the inner surface of the drum, and means acting to rotate said shaft and disks.

15

9. In a machine of the character set forth, the combination with a horizontally disposed cylindrical drum having an upper inlet at one end and a lower outlet at the other end, of a shaft axially extending through said drum, and spaced disks arranged on said shaft for rotation therewith within the drum, the disks being inclined relative to said shaft and having peripheral teeth parallel to the shaft in bearing coaction with the inner surface of the drum.

20

10. A device of the class described comprising a horizontal cylinder having end closures and an upper inlet at one end and a lower inlet at the other end, and a control valve associated with said outlet, a motor driven shaft journalled to said end closures and having fixed thereon a plurality of spaced parallel inclined disks provided with milled edges bearing against the inner surface of said cylinder.

25

11. A device of the class described comprising a cylinder having end closures and an upper inlet at one end and a lower inlet at the other end, a control valve associated with said outlet, and a motor driven shaft journalled to said end closures and having fixed thereon a plurality of spaced parallel inclined disks provided with milled edges bearing against the inner surface of said cylinder.

30

12. A device of the class described comprising relatively rotatable members consisting of a drum and a plurality of inclined disks arranged within the drum, the drum having a smooth inner bearing surface in the shape of a cylinder, and the disks having milled edges in bearing engagement with said bearing surface, the disks being disposed in fixed spaced parallel relation to each other, and means for rotating one of said members relative to the other, there being an upper inlet at one end of the device and a lower outlet at the other end thereof, said outlet having an adjustable valve for controlling the action of the device.

35

13. A device of the class described comprising relatively rotatable members consisting of a drum and a plurality of inclined disks arranged within the drum, the drum having a smooth inner bear-

40

ing surface in the shape of a cylinder, and the disks having milled edges in bearing engagement with said bearing surface, the disks being disposed in fixed spaced parallel relation to each other, and means for rotating one of said members relative to the other, there being an upper inlet at one end of the device and a lower outlet at the other end thereof.

14. In a device of the character set forth, the combination with a stator having an internal cylindrical bore provided with a smooth bearing surface, of a rotor having a plurality of spaced parallel inclined imperforate disks provided with toothed edges having a bearing fit with said bearing surface of the stator, there being an upper inlet at one end of said bore and a lower outlet at the other end thereof, the bore being arranged in a substantially horizontal position.

15. In a device of the character set forth, the combination with a stator having an internal cylindrical bore provided with a smooth bearing surface, of a rotor having a plurality of spaced parallel inclined imperforate disks provided with toothed edges having a bearing fit with said bearing surface of the stator.

16. In a machine of the class set forth, the combination with a cylindrical drum having a smooth internal surface and closed ends, of a rotor disposed within said drum and having a plurality of spaced parallel inclined imperforate disks provided with toothed edges coacting with the internal surface of said drum, the drum be-

ing arranged with its axis substantially horizontal and having an upper inlet at one end and a lower inlet at the other end thereof.

17. In a machine of the class set forth, the combination with a cylindrical drum having a smooth internal surface and closed ends, of a rotor disposed within said drum and having a plurality of spaced parallel inclined imperforate disks provided with toothed edges coacting with the internal surface of said drum.

18. A viscolizer capable of handling material containing abrasives without injury to itself, comprising a stator having an internal cylindrical bore provided with a smooth bearing surface, a rotor having a plurality of spaced parallel inclined imperforate discs provided with toothed edges in bearing coaction with said bearing surface of the stator, there being an upper inlet at one end of said bore and a lower outlet at the other end thereof, the bore being arranged in a substantially horizontal position, and a valve at the outlet for controlling the flow of material through the viscolizer.

19. A viscolizer capable of handling material containing abrasives without injury to itself, comprising a stator having an internal cylindrical bore provided with a smooth bearing surface, and a rotor having a plurality of spaced parallel inclined imperforate discs provided with toothed edges in bearing coaction with said bearing surface of the stator.

FRANK G. CRANE.
